UNITED STATES PATENT OFFICE.

ROSA AMELIA WHITEHOUSE, OF BIRMINGHAM, ENGLAND.

COMBINED CORSET AND CORSELET.

No. 883,125.

Specification of Letters Patent. Patented March 24, 1908.

Application filed May 29, 1907. Serial No. 376,243.

To all whom it may concern:

Be it known that I, ROSA AMELIA WHITEHOUSE, trading as Madame ROSA MELLEY, corsetiere, a citizen of England, and residing at 197 Broad street, in the city of Birmingham, in the county of Warwick, England, have invented certain new and useful Improvements in and Relating to a Combined Corset and Corselet, of which the following is a specification, such as will enable those skilled in the art to which it appertains to make and use the same.

This invention has reference to a combined corset and corselet.

In describing this invention the corselet is attached to the top of the corset by means of eyelets or other suitable fastenings ornamental or otherwise, said eyelets being arranged on the corselet and corset opposite to each other and in pairs and securing the garments together by means of ribbons or suitable lacings thus forming a trimming and hiding the division thereby making the combined garments appear as one.

By the removal of the ribbons or lacings the corselet can be removed and the corselet or corset worn separate as fashion or fancy dictates, each part being complete in itself. This invention is particularly applicable to the present fashion of Empire dress or with corselet skirt as now worn.

One great advantage achieved by thus attaching the two garments together is that in case of undeveloped busts, the bust of the corselet can be padded and naturally rounded without fear of slipping out of place, also in the opposite case when the bust of wearer is required by reason of fullness to be reduced this can be done by tightening lacing across the bust without the least possibility of slipping.

In reference to the accompanying drawings Figure 1 is a general view of the combined corset and corselet arranged according to this invention; Fig. 2 is a front view of the same without any trimming and showing how the corset and corselet may be attached to each other. Fig. 3 is a side view of the same, and Fig. 4 shows the corset and corselet separate.

In the practice of my invention, I provide a corselet 1 and a corset 3; and the top portion of the corset extends above the waist line when in position and is enlarged as clearly shown in the drawing and the corselet 1 is attached to the top 2, of the corset 3, by

means of eyelets 4, 5 or other suitable fastenings may be used, the said eyelets 4, 5 being arranged on the corselet 1, at the bottom edge 6, and on the corset at the top edge of 60 the same being opposite to each other, see Figs. 2, 3, the corselet 1 being secured to the corset 3 by ribbons or suitable lacings 8 the same forming a trimming and hiding the division or separate trimming 9 may be used to 65 hide the lacing 8, or other fastening, see Fig. 1.

By the removal of the ribbons or lacing 8 the corselet 1 can be removed from the corset 3 and the corselet 1 or corset 3 worn separate 70 as fashion or fancy dictates, each part being complete in itself, see Fig. 4. This combination is particularly applicable to the present fashion of Empire dress or with corselet skirt as now worn.

One great advantage achieved by thus attaching the two garments together is that in case of undeveloped busts, the bust 10 of the corselet 1 can be invisibly padded on the inside and naturally rounded without fear of 80 slipping out of place, also in the opposite case when the bust of wearer is required by reason of fullness to be reduced this can be done by tightening the lacing 11 across the bust of wearer without the least possibility of slip- 85 ping.

What I do claim as my invention and to secure by Letters Patent, is:—

1. A combined corset and corselet, the top portion of the corset extending above the 90 waist line when in position and being enlarged, the bottom edge of the corselet and the top edge of the corset being adapted to fit one within the other, and means for connecting said parts.

2. A combined corset and corselet, the top portion of the corset extending above the waist line when in position and being enlarged, the bottom edge of the corselet and the top edge of the corset being adapted to fit 100 one within the other, and means for connecting said parts consisting of eyelets placed in both of said parts and a lace cord passed therethrough.

In testimony that I claim the foregoing as 105 my invention I have signed my name in presence of the subscribing witnesses this 13th day of May, 1907.

ROSA AMELIA WHITEHOUSE.
